SPOON OR SIMILAR ARTICLE OF FLATWARE

Edward J. Conroy, Meriden, Conn., assignor to The International Silver Company, Meriden, Conn., a corporation of Connecticut

Application April 5, 1957, Serial No. 45,610

Term of patent 14 years

(Cl. D54—12)

Fig. 1 is a front elevational view of a spoon, showing the essential features of my new design in full lines; Fig. 2 is an enlarged cross section taken on the line 2—2 of Fig. 1;

Fig. 3 is an enlarged cross section taken on the line 3—3 of Fig. 1; and

Fig. 4 is a side elevational view of the spoon shown in Fig. 1.

The back of the spoon handle is substantially plain and follows the contours of the front as shown in Figs. 2, 3 and 4.

The design is intended for use on sets comprising spoons, forks, knives and similar articles of flatware.

I claim:

The ornamental design for a spoon or similar article of flatware, substantially as shown and described.
